UNITED STATES PATENT OFFICE.

JOHN E. LOGAN, OF WASHINGTON, DISTRICT OF COLUMBIA.

CENTRIFUGAL GOLD-EXTRACTING MACHINE.

Application filed February 7, 1925. Serial No. 7,550.

My invention relates to centrifugal gold extracting machines, and one object is to produce a machine of this character in which the process of extracting the precious metals from metalliferous materials will be continuous, and in which the precious metals are separated from the metalliferous materials in a minimum period of time, to the end that large quantities of metalliferous materials may be handled expeditiously and economically.

A further object of the invention is to provide a machine in which loss of precious metals is overcome, or at least reduced to a minimum by introducing the metalliferous materials into the bottom of a centrifugal extracting receptacle and lifting the sludge from which the precious metals have been extracted over the top of said receptacle by centrifugal conveyers, instead of permitting the sludge to flow off by the force of gravity as in ordinary practice.

Other features will hereinafter appear, and in order that the invention may be fully understood, reference will now be had to the accompanying drawings, in which:

Fig. 1 is a side elevation of the machine.

Fig. 2 is a broken central vertical section of the machine on line II—II of Fig. 1.

Fig. 3 is a fragmentary side elevation of a centrifugal conveyer constituting an important feature of the invention.

Fig. 4 is a cross section of the machine on line IV—IV of Fig. 1.

Fig. 5 is an irregular section of a distributor on line V—V of Fig. 2.

In carrying out the invention, I employ a hopper 2 into which the metalliferous material, supplied with water to form a solution, is fed and descends by the force of gravity through a feed tube 4 to a distributor 6, which spreads the material in its passage to the lower portion of a rotary bowl-shaped receptacle 8. The distributor 6 is spaced from and united to the flaring lower end 10 of the feed tube 4 by curved ribs 12, as shown by Fig. 2.

The hopper 2, the feed tube 4 and the distributor 6, rotate as a unit and are driven by an axially-disposed shaft 14, which is threaded at its lower end in said distributor 6 and suspended at its upper end from a collar 16 to which it is connected by suitable means such as a transverse pin 18. The shaft 14 is driven by a fixedly-mounted pulley 19 and journaled in bearings 20 and 21,

located at the upper portion of a frame 22, which supports various parts of the machine, as shown by Fig. 1. The bearing 20, in addition to coacting with the bearing 21 60 in supporting the shaft 14, also constitutes a step bearing for the collar 16.

The bottom portion 24 of the receptacle 8 is provided with a centrally-disposed depending boss 26 in which the upper end of 65 a drive shaft 28 is fixedly mounted to support and drive said receptacle 8. The drive shaft 28 is arranged in axial alinement with the drive shaft 14 and driven in a reverse direction thereto by a fixedly mounted pulley 30. Bearings 32 and 34 are provided at the lower portion of the frame 22 to support the drive shaft 28.

The circular wall of the receptacle 8 is provided at its lower portion opposite the 75 distributor 6 with a shallow annular chamber 36 separated from a similar superimposed chamber 38 by an annular flange 40, which projects inwardly and downwardly to prevent or retard the gold or other precious metal discharged by the distributor 6 from passing with the sludge to the upper portion of the receptacle 8. The upper portion of the chamber 38 is provided with a flange 42, which is similar to and coacts 80 with the flange 40 in retaining the precious metal in the lower portion of the receptacle 8. Outlets 44 are formed in the bottom of the chamber 36 through which the concentrates may be removed from the receptacle 80 85, said outlets being normally closed by screw plugs 46. The upper portion of the receptacle 8 has an inwardly extending rim 48 provided with a down and outturned marginal lip 49 to prevent the material 90 from being thrown out of the top of said receptacle by centrifugal force.

The sludge is lifted over the top of the receptacle 8 and deposited in an annular chute 52 by a pair of tubular centrifugal 100 conveyers 50. The chute 52 surrounds the receptacle 8 and is supported by arms 53 on the frame 22 and has an inclined bottom 54 leading to a spout 56 which discharges the sludge on the dump. As disclosed by 105 Figs. 2 and 4 the conveyers 50 are of peculiar shape, they being curved in vertical and horizontal planes to bring their respective inlets 57 down into the receptacle 8 to take up the sludge, and their outlets 58 into the chute 110 52 in a reverse position to the direction of rotation to prevent undue splashing of the

sludge against the interior of said chute 52. Each conveyer 50 is provided at opposite sides of its forward portion with fenders 60, so that as said forward portion travels in a circle through the sludge the same will be prevented from splashing upwardly by said fenders 60. Each conveyer 50 is also provided with a backwardly inclined arm 62 bolted to the outer fender 60 and provided with a plurality of forwardly inclined trimming devices, preferably, in the form of blades 64.

The conveyers 50 are connected to the extension hub 66 of a drive pulley 68 by arms 15 70. Said hub 66 is mounted in a ball bearing 71 carried by a yoke 72 secured to brackets 74 on opposite sides of the frame 22. The pulley 68 drives the conveyers 50 clockwise and in a reverse direction to the receptacle 8.

20 A loose sleeve 75 is interposed between the feed tube 4 and the hub 66 to prevent said feed tube from vibrating and to hold it in concentric relation with the hub 66, said sleeve 75 being supported by a collar 76 fixed to the tube 4. Material spilt over the upper edge of the hopper 2 is prevented from flowing down the exterior thereof and entering the open top of the drive pulley 68 and damaging the sleeve 75 and associate parts, 25 30 35 40 45 50 55 60 65 70 75 80 85 90 95 100 105 110 115 120 125 130

In practice the gold bearing material is passed in a screened, pulverized, crushed, or pulp condition into the hopper 2 with sufficient water to form a solution which will pass freely through the machine without clogging. The material flows from the hopper 2, through the feed tube 4 by the force of gravity aided by the rotary action of said feed tube 4 and the drive shaft 14. The material is directed by the feed tube 4 to the distributor 6 located in the lower portion of the receptacle 8, and the material is spread in a thin sheet as it passes over said distributor 6 from which it is discharged by centrifugal force into the lower portion of the receptacle 8, where the heavier along with some of the lighter particles of gold are entrapped in the chambers 36 and 38, while the remainder of the lighter particles ascend with the material along the inner surface of the circular wall of the receptacle 8 until checked by the rim 48. The ascending wall of material increases in thickness until it contacts with the blades 64, which, extending aslant downwardly and backwardly as shown by Fig. 3, throw the contacting material into the lower portion of the receptacle 8 where more of the particles of gold are thrown by centrifugal force into the chambers 36 and 38. As the material accumulates in the receptacle 8 it is formed by centrifugal force into a vortex in which the gold finds its way to the chambers 36, 38, and the interior surface of the circular wall of the receptacle 8,

while the sludge, being lighter, is forced towards the feed tube 4 and on reaching a certain level is taken up by the rotary conveyers 50, the inlets 57 of which are arranged close to said feed tube 4 and out of the zone 70 of the gold-bearing material. As the conveyers 50 carry off the sludge as fast as the gold-bearing material enters the receptacle 8, a substantially constant level is maintained and danger of an overflow is obviated, enabling constant operation of the machine as long as desired. When the machine is stopped the plugs 46 are removed and the concentrates are washed through the outlets 44. When desired an amalgamating agent, such as mercury may be placed in the chamber 36 to facilitate the segregation of the precious metal from the material.

From the foregoing description, taken in connection with the drawings, it will be understood that there is no overflow of tailings from the receptacle 8 with consequent loss of precious metal as in common practice, but on the contrary the material from which the previous metal has been extracted is lifted from said receptacle 8 by the conveyers 50, the inlets 57 of which are spaced a considerable distance from the chambers 36 and 38 in which the concentrates are accumulated by the force of gravity aided by centrifugal force.

It will also be understood that I have provided a machine having maximum capacity with little or no loss of precious metal, and while I have shown and described the preferred construction, combination and arrangement of parts, I reserve the right to make such changes as properly fall within the spirit and scope of the invention as claimed.

Having thus described my invention, what I claim and desire to secure by Letters Patent, is:

1. A machine of the character described consisting of a centrifugal receptacle, and a centrifugal conveyer extending over the top of the receptacle and having its forward end arranged interiorly and its rear end exteriorly of said receptacle.

2. A machine of the character described consisting of a receptacle, and a centrifugal tubular conveyer extending over the top of the receptacle and having its inlet end arranged interiorly and its outlet end exteriorly of said receptacle.

3. A machine of the character described consisting of a receptacle, a centrifugal conveyer extending over the top of the receptacle and having its forward end arranged interiorly and its rear end exteriorly of said receptacle, and fenders fixed to said conveyer at opposite sides of its forward portion.

4. A machine of the character described consisting of a circular receptacle, a cen-

- trifugal conveyer extending over the top of the receptacle and having its forward end arranged interiorly and its rear end exteriorly of said receptacle, and a trimming 5 device mounted on said conveyer and spaced a short distance from the interior surface of the receptacle.
5. A machine of the character described consisting of a circular receptacle, a central trifugal conveyer extending over the top of the receptacle and having its forward end arranged interiorly and its rear end exteriorly of said receptacle, an arm secured to the forward portion of said conveyer, and 10 blades carried by said arm and spaced a short distance from the interior surface of the receptacle.
6. A machine of the character described consisting of a centrifugal receptacle, a pair 15 of oppositely-disposed conveyers extending over the top of the receptacle and having their forward ends arranged interiorly and their rear ends exteriorly of said receptacle, and mechanism for driving the conveyers and said receptacle in reverse directions.
7. A machine of the character described consisting of a receptacle, a centrifugal conveyer mounted independently of and extending over the top of the receptacle and having its forward end arranged interiorly and its rear end exteriorly of said receptacle, and a chute into which said conveyer discharges.
8. A machine of the character described 25 consisting of a centrifugal receptacle, oppositely disposed centrifugal conveyers mounted independently of and extending over the top of the receptacle and having their forward ends arranged interiorly and their rear ends exteriorly of said receptacle, and an annular chute surrounding said receptacle and into which said conveyers discharge.
9. In a machine of the character described, 30 a centrifugal receptacle, a feed tube extending into said receptacle, a distributor arranged within the receptacle and at the lower portion of said feed tube, and means for driving said receptacle and the feed tube in reverse directions to each other.
10. In a machine of the character described, 35 a receptacle, a distributor located in said receptacle and provided at its upper portion with ribs, a feed tube extending into said receptacle and having a flaring lower end spaced above the distributor and fixed to said ribs, and mechanism for rotating the receptacle and the distributor in reverse directions to each other.
11. In a machine of the character described, 40 a receptacle, a distributor located in said receptacle and provided at its upper portion with ribs, a feed tube extending into said receptacle and having a flaring lower end spaced above the distributor and fixed to said ribs, a hopper at the upper end of 65 said feed tube, a shaft extending axially through the feed tube and fixed to said distributor, and means for driving said shaft and the receptacle in reverse directions to each other.
12. In a machine of the character described, 70 a receptacle, a shaft upon which said receptacle is mounted, a support for said shaft, means for driving said shaft, a conveyer leading from said receptacle, a drive pulley upon which said conveyer is mounted, and a support for said pulley.
13. In a machine of the character described, 75 a feed tube having a flaring lower end, a distributor spaced below said flaring lower end, and curved ribs interposed between and connecting said flaring end and said distributor.
14. In a machine of the character described, 80 a feed tube having a flaring lower end, a distributor spaced below said flaring lower end, curved ribs interposed between and connecting said flaring end and said distributor, a drive shaft extending axially through said feed tube and connected to said distributor, and a support for said drive shaft.
15. In a machine of the character described, 85 a pair of oppositely-disposed tubular conveyers, and a centrally-disposed rotary member to which said conveyers are firmly secured.
16. A machine of the character described 90 consisting of a support, a receptacle having a closed bottom, a drive shaft journaled in said support and fixed to the bottom of said receptacle, a pair of oppositely-disposed conveyers extending over the top of the receptacle and having their forward ends arranged interiorly and their rear ends exteriorly of said conveyer, a drive pulley journaled in the support and to which said conveyers are fixed, an annular chute surrounding the receptacle and into which the conveyers are adapted to discharge material 95 taken from said receptacle, a feed tube leading axially into the receptacle, a distributor connected to and disposed beneath said feed tube, and a drive shaft journaled in the support and extending axially through the feed tube and fixed to said distributor.
17. In a machine of the character described, 100 a bowl-shaped receptacle having a closed bottom and provided at its upper margin with an internal rim provided at 105 its inner margin with a downwardly and outwardly projecting lip, superimposed annular chambers in the lower portion of said receptacle, and inwardly and downwardly projecting flanges surmounting said chambers.

In testimony whereof I affix my signature.
JOHN E. LOGAN.
